(57) **CLAIM**

The ornamental design for a heating vest, as shown and described.

DESCRIPTION

FIG. 1 is a front, right, and top perspective view of a heating vest, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view thereof; with the side panels affixed;

FIG. 10 is a perspective view of a heating vest, shown in a second embodiment; and,

FIG. 11 is a perspective view of a heating vest, shown in a third embodiment.

The broken lines shown in the drawings are included for the purpose of illustrating portions of the heating vest that form no part of the claimed design.
